George F. Voight.

UNITED STATES PATENT OFFICE.

GEORGE F. VOIGHT, OF OAKLAND, CALIFORNIA, ASSIGNOR TO ECONOMY PRODUCTS CORPORATION, A CORPORATION OF CALIFORNIA.

WALL CONSTRUCTION.

Application filed July 26, 1922. Serial No. 577,595.

My invention relates to improvements in wall construction particularly adapted for frame buildings, having sheathing boards secured across the face of the wall studs as 5 a backing for the exterior plastic composition, the sheathing boards provided with a covering of building paper prior to the application of the plastic material to protect them against any moisture that may penetrate through or be contained in the plaster. One of the objects of the present invention is the provision of building paper provided on its face side with furring ribs for spacing the wire netting commonly used for reinforcing boards.

A further object is to provide relatively soft fibrous furring members or ribs against 20 which the relatively hard wire netting may be securely bound without danger of injuring the netting or the galvanizing with which it is preferably coated, which injury would be likely to occur if the furring members were formed of metal and a metal-to-metal contact thereby obtained.

With the foregoing and still further objects and purposes in view which will appear as the description proceeds, my invention 30 resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings—

Figure 1 is a side elevation of a fragmental portion of the wall of a frame building constructed in accordance with my invention.

Figure 2 is a view in elevation of a roll of the builders' paper comprising one of the 45 elements of my wall construction; a portion of the paper being shown un-rolled.

Figure 3 is a sectional view on line 3—3, Fig. 2.

Figure 4 is a sectional view on line 3—3, 50 Fig. 2, but with the inner or body sheet of the paper removed.

Figure 5 is a sectional plan view approximately on line 5—5, Fig. 1, showing in addition

tion a wall stud disposed against the back of the sheathing boards. 55

Figure 6 is a vertical sectional view on line 6—6, Fig. 2, a portion being broken away.

Figures 7 and 8 are views of portions of the present invention in modified forms in which the spacing projections or ribs are provided with a filler element, and in which Fig. 7 is a sectional view approximately on line 3—3, of Fig. 2, with one of the filler elements inserted in the hollow of the furring rib; and Fig. 8, is a vertical sectional view on line 8—8, Fig. 2, showing filler inserted. 65

Figure 9 is a view in perspective of one of the filler elements.

Referring to the drawings in detail, 70 throughout which like reference characters designate like parts—

The numeral 10 designates supporting studs which form the skeleton of the wall of the building and to the outer sides of which are secured, by nailing or otherwise, sheathing boards 11, which are laid preferably 75 in close edge-wise order so as to form, as nearly as practicable, a continuous board sheathing of approximately equal thickness. 80

Upon the outer side of the sheathing 11 is disposed a layer of builders' paper 12, which comprises primary sheets 12', and secondary strips 13, the latter spaced suitable distances apart, vertically and extend longitudinally 85 along the length of the former and are intended to be permanently cemented thereto.

Into the body of the secondary strips 13, at regular intervals, are formed, by pressing suitable indentures across the face of the strips, furring ribs or projections 14.

It will be noticed that in Fig. 1 the strips 13 are disposed upon the primary sheet 12 at unusual distances apart vertically. While in practice it makes very little if any difference as to the exact disposition of the strips relative to the sheet, I, however, prefer to place them upon the sheet in regular and equally spaced order as best illustrated in Fig. 2. 100

The number of strips 13 disposed on a single sheet of the primary paper 12' is best determined by the width of the sheet, the distances the strips are spaced away from each, and the width of the strips. 105

The furring ribs 14, also the strips 13 if

desired, may be hardened and made additionally rigid by subjecting the same to a suitable cement bath, under pressure if preferred, or may otherwise be treated to give ⁵ same any desired rigidity.

The strips 13 are preferably arranged upon the sheets 12' so that the furring ribs 14 will be disposed in staggered formation, as indicated in Figs. 1 and 2.

10 15 designates plasterers' wire or netting, which comprises a plurality of inter-twisted wires formed into hexagonal meshes 16, and which netting is disposed against the outer sides of the ribs 14 and to which it is secured by means of fastening elements 17, which straddle portions of the netting in engagement with the ribs, and also straddle the ribs and are driven through the sheets 12' into the boards 11.

20 It is to be understood that any suitable wire netting, having suitable meshes, may be substituted for the netting shown and described herein; also that any suitable fastening devices may be employed instead of the elements 17; and also that said fastening elements, or devices, may be driven along side of the ribs 14 without straddling them, or may be driven directly through the ribs.

30 In Fig. 1, the heavy horizontal lines forming portions of the drawings of the plasterers' netting, indicate portions of the wires inter-twisted (refer to Fig. 5).

35 While throughout the drawings, inter-twisted portions of the netting 15 only are shown in engagement with the furring ribs 14, it is obvious that any portion of the netting may be disposed in engagement therewith and secured thereto by the fastening elements 17 driven through the paper 12 into the boards 11.

40 18 designates the plastic element forming the outer coating of my wall construction, which may be formulated and mixed in any

manner suitable and is preferably applied by spreading it against the face of the paper ⁴⁵ and on and around the meshes of the reinforcement.

The object of the netting 15 is to reinforce the plaster and to hold same in place against the face of the wall while in the plastic state. ⁵⁰

In the modification of the invention, as illustrated in Figs. 7, 8 and 9, the numeral 20 designates a filler element fitted snugly into the hollow of the ribs 14 and is intended to reinforce the walls of the ribs to prevent ⁵⁵ collapsing thereof when accidentally subjecting to an abnormal blow of a hammer or like hand tool, as when applying the reinforcement thereagainst.

The filler 20 may be formed of wood, cement, clay, papier-mâché, or any other suitable material. ⁶⁰

I claim:

1. In means of the character described, a sheet of paper having substantially parallel side edges, and a plurality of relatively narrow strips of paper disposed in spaced order across the face side of said sheet in parallelism with said side edges, said strips provided with spacing members adapted to support wire netting in spaced relation to said sheet. ⁶⁵

2. In means of the character described, a sheathing paper having an inner layer with an outer layer in separated strips, said strips being corrugated to form spacing ribs. ⁷⁵

3. In means of the character described, a sheathing paper having an inner layer with an outer layer in separated strips, said strips being corrugated cross-wise to form spacing ribs. ⁸⁰

In testimony of the foregoing being my own, I have hereunto affixed my signature this 20th day of July, 1922.

GEORGE F. VOIGHT.
